Frank S. Alden. Charles, messenger

United States Patent Office.

CHARLES MESSENGER, OF CLEVELAND, OHIO.

Letters Patent No. 70,010, dated October 22, 1867.

TOOL FOR OPENING SHEET-METAL CANS.

The Schedule referred to in these Letters Patent and making part of the same.

TO ALL WHOM IT MAY CONCERN:

Be it known that I, CHARLES MESSENGER, of Cleveland, in the county of Cuyahoga, and State of Ohio, have invented certain new and useful Improvements in Can-Openers; and I do hereby declare that the following is a full and complete description of the same, reference being had to the accompanying drawings, making a part of this specification, in which—

Figure 1 is a top view of the apparatus.

Figure 2 is a side view.

Figure 3 is a detached section.

Like letters refer to like parts in the views.

A, fig. 1, is a metallic plate fixed in a handle, B. In the outer end of this plate is a hole, in which is inserted a rod, C, the end of which is made to project beyond the end of the plate, and is brought to a sharp point, C', as shown in fig. 2. The inner end of this rod is held in place by a ring, D, surrounding the plate and rod, and which may be moved along upon the rod, or removed from it, for a purpose hereafter shown. E, fig. 2, is a blade or cutter slipped upon the rod, and projected downward through the plate, as shown in fig. 2.

The practical use of this instrument is for opening oyster, paint, fruit-cans, &c., and which is done in the following manner, viz: The apparatus is held in the right hand, and the point C' thrust through the centre of the top of the can. The handle is then brought down so as to cause the blade to penetrate the cover; the instrument is turned around the circumference of the top, the point acting as a pivot, and the handle as a lever; the blade, as the instrument turns, will cut out a round hole through which the contents of the can may be emptied. The size of a hole thus cut may be made greater or less, by shifting the blade from its present position, and making it pass through either of the holes a, fig. 1, and thus cut a small or a large hole as may be required.

Fig. 3 represents a form of knife that may be used in this instrument, and which consists of a centre, F, with radial arms G, said arms being brought down to a sharp edge, each arm having two edges.

The advantage of this knife is that when one blade is worn out or becomes dull, another is ready at hand for use by simply changing one for another, and which is done by slipping the ring from the rod, and thus allow the blade to be withdrawn from the plate and another inserted.

What I claim as my improvement, and desire to secure by Letters Patent, is—

The rod C, blade E, and ring D, in combination with the plate A, for the purpose and in the manner set forth.

CHARLES MESSENGER.
